UNITED STATES PATENT OFFICE

LEON B. CONANT, OF CAMBRIDGE, MASSACHUSETTS, ASSIGNOR, BY MESNE ASSIGNMENTS, TO STANDARD PATENT PROCESS CORPORATION, A CORPORATION OF MASSACHUSETTS

PROCESS OF VULCANIZING RUBBER TO LEATHER

No Drawing.

Application filed November 1, 1926. Serial No. 145,489.

In my companion application filed June 7, 1926, Serial No. 114,319, I have disclosed a process of vulcanizing rubber to leather, an essential step in which is a pre-heating of 5 the leather at a temperature substantially equal to that of vulcanization; and in my companion application filed October 4, 1926, Serial No. 139,345, I set forth an improvement upon the previous process consisting in 10 dehydrating the leather at a moderate temperature prior to its pre-heating.

These are most important improvements in the art because the pre-heating of the leather at a temperature substantially equal to that 15 employed in the subsequent vulcanization of the rubber composition thereto, assures its successful adaptation to the heat of its union therewith, which commonly exceeds 300° F., and if prior to its pre-heating, care is taken 20 to dehydrate the leather at a moderate temperature, preferably at less than 200° F., the very great advantage is secured of working a uniform material during its subjection to the pre-heating operation and following in- 25 troduction in company with the rubber to the heat of vulcanization.

Accordingly, since this process is designed 30 to accommodate all manner and kinds of leathers, for successful combination with rubber composition by hot vulcanization, it is necessary to dehydrate at moderate temperature, and thereby to assure the uniformity of 35 condition of the leather from then on, as it works its way through the process, this feature cannot be emphasized too strongly. This manner of dehydrating is extremely advantageous because it guarantees in combination with the pre-heating operation the retention 40 by the leather fibres of that prime condition or circumstance that later permits, as this process will describe, the full eventual restoration of fibre-toughness and therefore of 45 serviceability to the leather.

This process, therefore, has as its objective 50 the preservation of the original qualities in the leather throughout the several different steps of its manipulation or handling prior to, during and following its combination with the rubber, and, it is the application of these several steps in combination, and

in the natural sequence described, that together constitute the guarantee that the leather shall regain all of its attributes or qualities as originally possessed.

There is also another hazard in working 55 leather successfully that dehydration at a temperature of 200° F. or less overcomes, and that is the condition commonly found wherein pieces of leather are pasted or glued together, thereby permitting the utilization of 60 scrap or offal leather that, because of such assembly has become of greatly enhanced value and acceptability in many lines of manufacture, and particularly in shoe making.

If, therefore, such pasted or glued leather 65 is to be adapted to successful combination with rubber composition by hot vulcanization, even the most casual consideration enforces the realization that any medium, as glue, clogging the pores of the leather offal 70 to be prepared for processing, is a handicap that, if not recognized and controlled, would become a serious impediment, since, lying within the leather body, it is in effect a veneer 75 or coating quite likely to function as a very effectual blockade to the enforced movement of the normal moisture content of the leather upon its subjection to a temperature approaching that commonly employed in vulcanization, and, if disregarded, this coating 80 or veneer will surely become the agent of destruction ruining the vulcanized combination.

Accordingly, and as recited above, the act 85 of dehydration at a temperature less than 200° F. provides, because of the complete or partial presence or utilization of pasted or glued leather offal, that degree of accommodation requisite to adapt the leather offal to this process prior to its pre-heating at a much 90 higher temperature, since the comparatively low temperature of such dehydration slowly but surely removes the normal atmospheric content of moisture in the leather entirely 95 without injury to the leather fibres, and without disturbing the union between the pasted or glued parts, as the slowness of the drying-out creates no radical disturbance of the fibrous relationship or cohesion as promoted 100 by the paste or glue.

When, now, the leather has first been dehydrated at a temperature of 200° F. or less, and then pre-heated at a temperature substantially equal to that employed in its later combination with the rubber composition by hot vulcanization preferably with pressure, at ordinarily a temperature in excess of 300° F., and following such pre-heating has been vulcanized as described, there is now at hand the fruit of successful processing, the vulcanized combination leather and rubber article, but lacking withal such a degree of naturalness in so far as the leather is concerned, that the futility of further prohibition emphasizes and commends the value inherent in prompt and adequate restoration to normalcy.

Accordingly, the next step in this process is that of providing the leather with an abundance of moisture; and such moisture content being enforced, may be obtained either by means of a properly humidified atmosphere, or preferably by immersion in water. Having, therefore, soaked the leather in a water bath, which it absorbs with the appetite of a glutton, its fibres drink their fill and it becomes unserviceable; but by giving it a partial dehydration in a suitable atmosphere, the super-content of moisture is removed and the vulcanized article of leather and rubber is now perfectly ready for service.

The process may therefore be summarized as comprising the acts of dehydration at moderate temperature; pre-heating at vulcanizing temperature; bringing the leather while superheated into company with the rubber composition and vulcanizing the latter thereto; then restoring a normal moisture content by enforcing a super-abundance thereof, and then reducing the same by evaporation in a partially dehydrating atmosphere.

Where the articles thus produced are combination heels, they can be at once attached to footwear and properly trimmed to fit the same, without the swelling and consequent mis-fit which otherwise occurs, where there is no hydrating following vulcanization.

What I claim as my invention is:

1. The process of vulcanizing rubber to leather, consisting in first dehydrating the leather at a moderate temperature; then subjecting the leather to a temperature substantially equal to that of vulcanization; and then uniting and vulcanizing the rubber thereto.

2. The process of vulcanizing rubber to leather, consisting in first dehydrating the leather at a moderate temperature; then subjecting the leather to a temperature substantially equal to that of vulcanization; and then uniting and hot vulcanizing the rubber thereto.

3. The process of vulcanizing rubber to leather, consisting in first dehydrating the leather at a moderate temperature; then sub-

jecting the leather to a temperature substantially equal to that of vulcanization; uniting and vulcanizing the rubber thereto; immersing the leather in water; and finally drying it to retain a normal amount of moisture.

4. The process of vulcanizing rubber to leather, consisting in first dehydrating the leather at a moderate temperature; then subjecting it to a temperature substantially equal to that of vulcanization; and then uniting and vulcanizing the rubber thereto with heat and pressure.

5. The process of vulcanizing rubber to leather which consists in dehydrating the leather at a moderate temperature, then pre-heating the dehydrated leather at an elevated temperature thereby energizing the leather with a super-heat, and then while so energized with heat bringing it in company with rubber into the heat of vulcanization and uniting and vulcanizing the rubber thereto; and finally re-hydrating the leather by introducing the vulcanized combination into water for a suitable time.

In testimony that I claim the foregoing invention, I have hereunto set my hand this 29th day of October, 1926.
